UNITED STATES PATENT OFFICE.

CHARLES F. LOCKHART AND EVERETT H. ROBY, OF CLEVELAND, OHIO.

WASHING-MACHINE POUNDER.

1,418,587.

Specification of Letters Patent. Patented June 6, 1922.

Application filed July 25, 1921. Serial No. 487,388.

To all whom it may concern:

Be it known that we, CHARLES F. LOCKHART and EVERETT H. ROBY, citizens of the United States, residing at Cleveland, in the 5 county of Cuyahoga and State of Ohio, have invented certain new and useful Improvements in Washing-Machine Pounders, of which the following is a specification.

This invention relates to suction cups 10 adapted and intended for use in washing machines, and particularly in that type of washing machine known as pounder machines in which, ordinarily, a plurality of suction cups are caused to work up and 15 down, thereby forcing the water through the clothes in opposite directions alternately.

The object of the present invention is to produce an improved cup for the purpose stated. When used, the action of this cup is 20 to first compress the clothes; then the piston in the neck of the cup forces the air and water in the cup through the clothes. The cup continues to be held with pressure against the clothes by means of a spring in 25 the neck of the cup, and when the piston is moved upward there is a vacuum action which draws the water back through the clothes in the opposite direction, and at the same time the suction causes the clothes to 30 adhere to the mouth of the cup until they are lifted up in the water, permitting the water from the surrounding part to rush in under the clothes, and on the next stroke the cup is forced down, carrying the clothes with it, 35 and then the piston descends and the operation above described is repeated. This action results in a very powerful cleaning effect on the clothes and produces a superior washing action.

40 In the accompanying drawing Fig. 1 is a vertical section of one of the cups. Fig. 2 is a section on the line 2—2 of Fig. 1.

Referring specifically to the drawing, 6 indicates a dasher head or spider which carries 45 the cups, a part only of this element being shown, as a plurality of cups are or will be attached thereto. The cup proper is indicated at 7, consisting of a frusto conical member, preferably made of sheet metal, and 50 having an outstanding flange 8 at the mouth or bottom. At the top the cup is formed with a sleeve 9 forming a cylinder or barrel which reciprocates on a hollow plunger 10 the head of which may have a leather packing indicated at 11 to make it water tight, 55 this packing being fastened to the head of

the plunger by a washer 12 and screw 13 or in any other suitable manner. The upper end of the plunger is threaded and is screwed into the dasher 6, as indicated at 60 14, projecting somewhat above the dasher to receive a screw cap 15 which locks the plunger in place and also serves to close the upper end thereof. Within the plunger is a coiled spring 16 which is confined in compression between the cup 15 and cross rods 17 65 which are secured to the upper end of the neck or barrel 10 and which work in slots 18 in the side wall of the plunger. These slots limit the length of the stroke of the 70 cup with respect to the plunger, and the head of the plunger, in the barrel, acts to produce suction within the cup.

In operation, when the dasher descends the bottom of the cup comes in contact with 75 the clothes, and water is thereby forced up through the clothes. On further descent of the dasher, when the pressure exceeds the strength of the spring 16, the plunger moves down in the barrel 9 and the water and air 80 if any trapped in the cup is thereby forced out through the clothes until the stroke of the dasher is completed. Then the dasher lifts. The spring holds the cup in contact with the clothes, and as the plunger lifts, the 85 water is again sucked in through the clothes until the plunger reaches the limit permitted by the slots 18. Then the plunger picks up the cup and the clothes adhere thereto and are lifted with the cup to the top of the water 90 in the tub or thereabouts. Then the plunger again descends and the operation is repeated. There are thus four separate actions at each 95 complete stroke of the dasher: the first is the cup compression against the clothes; the second is the piston action of the plunger in the barrel, forcing the water downwardly through the clothes; the next is the piston action when the plunger lifts, thereby sucking the water up through the clothes; and finally the lift of the cup and the clothes adhering thereto. This produces a very superior cup for the intended purpose.

We claim:

1. The combination with a dasher, of a 105 hollow plunger attached thereto and depending therefrom, the lower end of the plunger being closed, a suction cup having a barrel at the top in which the plunger fits slidably, and a spring enclosed within the plunger 110 and operatively connected to the barrel and tending to force the cup downwardly.

2. A device of the kind described comprising a suction cup having a barrel at the top thereof, a slotted plunger movable up and down in the barrel and adapted to be connected to a dasher, a cross piece connected to the barrel and extending through the plunger, and a spring in compression between the cross piece and the plunger.
3. A device of the kind described comprising a suction cup having a pump barrel at the top, a hollow plunger working in said barrel, said plunger having slots in its side walls a dasher connected to the upper end

of the plunger, a rod extending through the slots and connected to the barrel, and a 15 spring enclosed in the plunger and confined between the upper end thereof and the said rod.

In testimony whereof, we affix our signatures in presence of two witnesses.

CHARLES F. LOCKHART.
EVERETT H. ROBY.
